[57] ABSTRACT

An apparatus for generating a wobble motion with a wobble body is disclosed. An endless band is secured to the wobble body for transmitting motion thereto. The endless band is formed of a flat circular ring band which is bent about axes parallel to two perpendicular diameters. In position, the endless band includes a symmetry plane which extends through one of the body suspension means. A drive mechanism secured to a frame imparts motion to the wobble body via the endless band. The wobble body is rotatably secured to a frame by suspension means.

APPARATUS FOR GENERATING A WOBBLE MOTION

BACKGROUND OF THE INVENTION

The present invention relates to a new and improved construction of apparatus for generating a wobble or tumbling motion.

Such equipment is known to the art and, for instance, has been disclosed in Swiss Pat. No. 216,760. Apparatuses of this type up to the present have been driven via two shafts which move in opposite directions and with alternately decelerating and accelerating motion. This requires a rather complicated and especially expensive drive mechanism which additionally is associated with poor efficiency.

Bodies moving with a wobble or tumbling motion, especially if they have a shape accommodated to the momentarily encountered special field of use, can be employed with great efficiency for instance as jarring containers in jarring machines or also as repulsion elements for ship drives. The thus attained advantages in comparison with conventional systems are particularly then significant if they are employed with efficient drive mechanisms.

SUMMARY OF THE INVENTION

Hence, it is a primary object of the present invention to provide an improved construction of apparatus for generating a wobble or tumbling motion and which apparatus is not associated with the aforementioned drawbacks and limitations of the prior art proposals.

Generally speaking, the present invention relates to an apparatus for generating a wobble motion by means of a wobble body and which motion is defined by the movement of the central element of a uniform three-part chain turned inside-out, and the wobble body being mounted in a frame such that it can only carry out such wobble motion, there also being provided a drive mechanism.

According to the invention and for the purpose of avoiding the previously discussed drawbacks, the apparatus of this development is manifested by the features that an endless band produced by the crosswise opposed curving of a circular ring about axes parallel to two perpendicular diameters is secured to the wobble body in such a manner that a respective one of its planes of symmetry extends through a respective one of the suspension devices of the body and which suspension devices intersect one another, and the open ends of the perpendicular respective projection of the band extends towards the respective symmetry plane of the respective suspension device and in each instance possesses the same spacing therefrom, and further, that as the drive for the band there is provided at least one drive means arranged such that its point of attack or engagement with the band is located at the central plane between the bearing locations or bearings of the wobble body at the frame.

Advantageously, the drive means consists of one friction wheel, or for the purpose of increasing the frictional force, also two friction wheels symmetrically arranged with regard to one another and with respect to the band. In order to balance out or compensate for possible irregularities of the apparatus, it is advantageous if the friction wheels are elastically mounted. Particularly suitable for use as the wobble body are the

connection-torsos of two circles which emanate from uniform turning inside-out kinematics.

BRIEF DESCRIPTION OF THE DRAWINGS

The invention will be better understood and objects other than those set forth above, will become apparent when consideration is given to the following detailed description thereof. Such description makes reference to the annexed drawings wherein:

10 FIG. 1 is a perspective view of a first exemplary embodiment of the invention;

FIG. 2 is a perspective view of a second exemplary embodiment of the invention;

15 FIG. 3 is a detail of a variant of the apparatus depicted in FIG. 2;

FIG. 4 is a perspective view of a fourth exemplary embodiment of the invention; and

20 FIG. 5 is an exemplary embodiment of the invention which is a combination of the embodiments depicted in FIGS. 3 and 4.

DETAILED DESCRIPTION OF THE PREFERRED EMBODIMENTS

Describing now the drawings, in FIG. 1 there is illustrated a conventional suspension mechanism for generating a wobble motion. In particular, it will be recognized that in a frame or housing 1 there are mounted parallelly rotatable two shafts 2 having bifurcated or fork-like ends 2a and these shafts are secured against axial displacement by any suitable and therefore not particularly illustrated means. Between the two prongs or legs 2c of each of the fork-shaped or bifurcated shaft ends 2a there is pivotably mounted by means of a respective axle bolt 2b a respective approximately U-shaped bracket 3. Both ends of each bracket 3 possess a respective pin 3a. These pins 3a serve for the attachment of a wobble body 4 and are pivotably mounted in bearing bushings or sleeves 3b arranged at the surface of wobble body 4. The connecting lines of each two respective pins 3a mounted at their bracket 3 extend in two directions which are perpendicular to one another.

the other pin pair. This spatially curved endless band 5 consists of a flat circular ring band bent cross-wise in opposed relation about axes which are parallel to two perpendicular diameters. In each case two radii of the original circular band and which radii extend through the points of most pronounced curvature form an angle of 120°. The size of the band 5 basically is of no significance, yet the inner radius of the generating circular band at least must correspond approximately to the value, multiplied by a factor of 1.2, of the spacing of the connection lines of each two respective pins 3a.

Under these preconditions, during the wobbling motion of the wobble body 4 and therefore the band 5 connected therewith, the radii of the band travel through a spatially fixed line 5b, and specifically that line which is parallel to the shafts and extending through the point of bisection of the spacing of their axes. Furthermore, all points of the band, the spacing of which from its inner and outer edge are of the same magnitude, move uniformly. In this manner it is thus possible to uniformly drive a system of the previously described type for generating a wobble motion. To this end there is secured to a drive shaft 6 mounted at the frame 1a drive member such as a friction wheel 6a (which also may be a gear) which is in engagement with the band 5 exactly along the previously mentioned spatially fixed line 5b. Instead of employing the friction wheel it would also be possible to use a slightly conical gear. For the friction drive there can be realized a force transmission free of slip by application of an elastic layer to the endless band.

Since the speed of individual band points is dependent upon their spacing from the edge of the band, there results therefrom the advantage that the speed of the wobble motion can be infinitely controlled in the simplest manner without the need to employ reduction gearing. To this end the friction wheel 6a is displaced axially in the direction of the outer edge of the band when the speed should be reduced, and towards the inner band edge when the speed should be increased, the rotational speed of the drive shaft 6 remaining constant.

Equipment with wobble bodies are employed in jarring machines, wherein the wobble body serves as a jarring container. In FIG. 1 the wobble body 4 therefore possesses an infeed and outfeed opening 4a. The wobble body which is known from the aforementioned Swiss Pat. No. 500,000, has an ideal form as a mixing container, however, also can be replaced for instance by a cylindrical vessel 7 with an opening 7a, as such has been illustrated for instance in FIG. 2 in accordance with a second exemplary embodiment of the invention. This arrangement corresponds completely to that depicted in FIG. 1 and accordingly corresponding components have been indicated by reference characters which have been increased by the number 10, for instance shafts 2 of FIG. 1 are identified by reference character 12 in FIG. 2 and so forth. The cylinder 7 could be constructed for instance only as a support for an actual jarring vessel, which then would be mounted therein and can be there fixedly retained in order to be capable of again being removed following the jarring operation.

In order to render possible a continuous charging and removal of the material which is to be jarred, there are introduced into the wobble body 27 which has only been partially illustrated in FIG. 3, two hoses 28,

wherein a respective hose section 28b is connected through the agency of a suitable coupling, such as coupling 28a permitting relative rotation between two parts, with a hose section 28c which is guided through a shaft 22 constructed as a hollow shaft and provided with a bifurcated or forked end 22a. In FIG. 3 for the sake of preserving clarity in illustration, there has only been depicted one of the hoses 28. The wobble body 27 is mounted by means of the brackets 23, only one of which is visible. At the region of a respective bearing bushing or sleeve 23b the wobble body 27 possesses a respective connection opening 27a for the hoses 28.

Now in FIG. 4 there is depicted a further exemplary embodiment of the invention. This embodiment of the invention differs from the first three embodiments by a novel type of mounting of the wobble body 34, which in this instance again advantageously possesses the shape of the already mentioned wobble body of FIG. 1 and that described in greater detail in Swiss Pat. No. 500,000. The wobble body 34 is here provided with slide runners or skids 39 forming arcs of slightly more than 240°, and these runners 39 are located in two planes disposed perpendicular to one another and in a position where the concave sides confront one another, and further, wherein each runner forms the symmetry plane for the other. The entire body 34 is connected in such a manner with the drive band 35 that its center of gravity coincides with the common center of gravity of the pair of slide runners 39 and each runner plane is located in one of the symmetry planes of the band. The curvature of the band thus corresponds to that of the momentarily closer situated slide runner. The runners 39 are guided in a respective flexible bearing bushing or sleeve 32c each of which, in turn, is connected with a respective shaft 32 rotatably mounted at the frame or housing 31. The drive shaft 36 with the friction wheel 36a extends parallel to both shafts 32, through the bisection point of the connection line of the latter.

The entire arrangement is dimensioned such that the spacing between the curvature centers of the runners is equal to their radii of curvature and the spacing between both shafts 32 corresponds to the radius of the runners multiplied by the factor 3. In the event, as is the case with the embodiment under consideration, the wobble body possesses a form which is derived from the kinematics of turning a body inside-out and as is known from Swiss Pat. No. 500,000 with only slightly smaller characteristic sizes than that of the drive system, then the band 35 can be mounted directly at the wobble body at its central line, as such has been depicted in FIG. 4.

Of course, the runners 39 also could be secured to any other body, for instance a cylinder, however then the band 35 must be fixed thereto via webs or struts.

In the event the wobble body is hollow, then this equipment also can be employed as a jarring machine.

When using a wobble body with the previously disclosed particular shape, the equipment of the invention disclosed in conjunction with FIG. 4 also constitutes a particularly effective repulsion element, for instance for the drive of a ship. This special wobble body itself as well as also the band possesses outstanding hydrodynamic efficiency. Up to now this could not be made use of since the cumbersome mounting of the wobble body in brackets and the disadvantageous drive via the bearing shafts again destroyed the good efficiency.

A particularly interesting possibility is realized if the embodiments depicted in FIGS. 3 and 4 are combined, as the same has been shown in FIG. 5. The shafts 42 are constructed as hollow shafts and connected through the agency of rotatable hose couplings 48a with a respective infeed- and outfeed conduit 48b. Each hose section 48c which extends out of the associated hollow shaft 42 slightly above the associated sleeve or bushing 42c, as shown, is connected to the wobble body 44 by a respective connection nipple 44a. The entire system is mounted in a closed container 41. However, one of the conduits 48b is connected with the container 41, as shown at the right of FIG. 5. The container 41 further possesses a discharge opening 41a and a discharge conduit or line 41b connected therewith. By virtue of this construction there can be realized in continuous manner a particularly intimate double mixing of materials which are to be jarred. On the one hand, mixing can occur in the jarring vessel 44 and, on the other hand, by its repulsive action in the container 41.

In the event that the container 41 is omitted and the entire system mounted in the manner depicted in FIG. 4, then there is attained a simpler jarring mechanism.

A further field of use resides in the field of water purification. For instance, a ship travelling upon the ocean could be driven by means of the apparatus and at the same time the sea water could be conducted through the inner compartment of the wobble body which contains silver granulates and thus such sea water freed in a particularly simple and effective manner from pathogenic bacteria and germs. Also it is mentioned that the endless band can be provided with ribs or teeth, if desired.

While there is shown and described present preferred embodiments of the invention, it is to be distinctly understood that the invention is not limited thereto, but may be otherwise variously embodied and practiced within the scope of the following claims.

What is claimed is:

1. An apparatus for generating a wobble motion with a wobble body, said wobble body being mounted via suspension means at a frame such that it can carry out only one predetermined wobble motion, and a drive mechanism, the improvement comprising an endless band having crosswise opposed portions symmetrically curved with respect to two perpendicular symmetry

planes about axes extending perpendicular to said planes respectively, each of said suspension means possessing a respective pivot axis, said band being secured to the wobble body such that a respective one of its symmetry planes is perpendicular to a respective pivot axis of the associated suspension means, the imaginary connecting lines extending between opposed points of maximum curvature of said band being situated closer to the associated suspension means than the center of gravity of the curved band, and the drive mechanism for the band comprising at least one drive means arranged such that its point of attack at the band is located substantially at the central plane between the mounting locations of the suspension means at the frame.

2. The apparatus as defined in claim 1, wherein the endless band is provided with ribs.

3. The apparatus as defined in claim 1, wherein the endless band is provided with teeth.

4. The apparatus as defined in claim 1, wherein said drive means for the band comprises a gear.

5. The apparatus as defined in claim 1, wherein said drive means for the band comprises a friction wheel.

6. The apparatus as defined in claim 1, wherein said drive means for the band possesses two drive wheels which are symmetrically arranged at the band with respect to the point of attack.

7. The apparatus as defined in claim 1, wherein the wobble body is provided with substantially arcuate-shaped runners located in two planes perpendicular to one another and with their concave sides confronting one another, said runners being secured at the endless band in such a manner that its center of gravity coincides with the common center of gravity of the pair of runners and a respective runner plane is located in a respective symmetry plane of the band, and the respective runner curvatures extend analogous to the projections of the band upon the respective symmetry plane, and said slide runners being slidably mounted in two flexible bearing bushings.

8. The apparatus as defined in claim 1, wherein the wobble body possesses the form of a hull body of a system formed of two arcuate-shaped runners located in planes perpendicular to one another and rigidly connected with one another.
